LUGGAGE CASE

John P. Ronvik, Chicago, Ill., assignor to Sears, Roebuck and Co., Chicago, Ill., a corporation of New York

Filed Aug. 14, 1963, Ser. No. 76,208

Term of patent 14 years

(Cl. D87—5)

FIG. 1 is a perspective view of a luggage case embodying my new design;

FIG. 2 is an end elevational view thereof;

FIG. 3 is an elevational view of the side opposite that shown in FIG. 1.

The essential features of my design are shown in full lines.

I claim:

The ornamental design for a luggage case, as shown and described.
